DESIGN FOR A DIRECTION SIGNAL LAMP FOR MOTOR VEHICLES

Henry J. Sauer, Fairfield, Conn., assignor to The
Kilborn-Sauer Company, Fairfield, Conn., a
corporation of Connecticut

Application November 25, 1938, Serial No. 81,354

Term of patent 7 years

To all whom it may concern:

Be it known that I, Henry J. Sauer, a citizen of the United States and a resident of Fairfield, county of Fairfield, and State of Connecticut, have invented a new, original, and ornamental Design for a Direction Signal Lamp for Motor Vehicles, of which the following is a specification, reference being had to the accompanying drawing, forming part thereof.

In the drawing:

Fig. 1 is a front view of a direction signal lamp for motor vehicles, showing my new design.

Fig. 2 is a plan view.

Fig. 3 is an end view.

I claim:

The ornamental design for a direction signal lamp for motor vehicles, substantially as shown.

HENRY J. SAUER.
